UNITED STATES PATENT OFFICE.

EDWIN W. SMITH, OF ST. CATHARINES, CANADA, ASSIGNOR OF TWO-THIRDS TO EDWIN POOLE AND EDWARD GANDER, OF ST. CATHARINES, CANADA.

TELEPHONE-CABINET.

SPECIFICATION forming part of Letters Patent No. 686,423, dated November 12, 1901.

Application filed March 21, 1901. Serial No. 52,264. (No model.)

To all whom it may concern:

Be it known that I, EDWIN W. SMITH, a subject of the King of England, residing at St. Catharines, in the Province of Ontario and 5 Dominion of Canada, have invented a new and useful Improvement in Telephone-Cabinets, of which the following is a specification.

This invention relates to a hood or cabinet adapted to be applied to a telephone-transmitter and constructed to inclose the head or upper portion of the speaker's person, so that a conversation can be carried on privately and without noise or disturbance, as in the telephone cabinets or compartments now in 15 common use.

The object of my invention is the provision of a compact and practically sound-proof inclosure which occupies less space and is less expensive than the ordinary telephone-cabinet and which can be readily applied to an ordinary telephone-transmitter.

In the accompanying drawings, consisting of two sheets, Figure 1 is a side elevation of a telephone provided with my improved hood. 25 Fig. 2 is a top plan view thereof, showing the doors of the hood open. Fig. 3 is a detached rear view of the hood. Fig. 4 is a face view of the bracket applied to the transmitter. Fig. 5 is a vertical longitudinal section of the 30 hood applied to the transmitter. Fig. 6 is a transverse vertical section in line 6 6, Fig. 5. Fig. 7 is a horizontal section in line 7 7, Fig. 5. Fig. 8 is a fragmentary vertical section in line 8 8, Fig. 7.

Like letters of reference refer to like parts in the several figures.

A is the transmitter-case of a telephone, and a its front plate. B is the receiver; B', the usual vertically-swinging forked switch-lever 40 which ordinarily supports the receiver.

C is my improved hood or cabinet, which is preferably removably attached to the transmitter-case and made of the proper size to freely receive the head and neck of a person.

45 The hood is closed on all sides and may be of any suitable form; but its rear wall C' is preferably straight, and its side walls C² converge toward its rear wall, while its front wall is formed by a pair of curved horizontally-swinging doors C³, hinged at d to the rear ends of

the side walls C², as most clearly shown in Figs. 1, 2, and 7. The hood may be constructed of any suitable material, as glass, wood, paper-board, celluloid, or aluminium, and its walls are preferably hollow or double to form 55 an intermediate non-conducting air-space. The side walls of the hood may be provided with glass panels, so that the occupant can look through the same for making memoranda on the usual desk adjacent to the telephone. 60

E is a bracket-plate detachably secured to the front plate a of the transmitter-case and provided at its side edges with hooks or clasps e, which embrace the projecting edge of the plate a, as shown in Figs. 1 and 7. The shanks 65 of these hooks are provided with longitudinal slots e', through which the fastening-screws of the hooks pass, thereby permitting the hooks to be adjusted to the thickness of the front plate a. 70

The rear side of the bracket-plate E may be covered with felt or similar material to prevent marring of the transmitter-case. This plate is provided on its front side with a vertical bar f, having undercut vertical edges f', 75 which slide in vertical guides or ways f², arranged on the rear wall of the telephone-hood C, as seen in Figs. 1, 3, 5, and 7, thus attaching the hood to the transmitter and at the same time allowing it to slide vertically to accommodate persons of different statures. 80

The hood is preferably counterbalanced by a spring-drum G or by a weight, the drum being connected with the top of the hood by a cord g, wound upon the drum, as shown in 85 Fig. 1.

h is an opening formed in the rear wall of the hood C and registering with a tube or opening h' in the bracket-plate E, which tube coincides with the diaphragm of the transmitter. The opening h is elongated vertically, so as to register with the tube h' in all positions of the hood. 90

As shown in Figs. 2 and 7, the hinged doors C³ are provided at their upper and lower ends 95 with horizontal quadrant-shaped plates i i', which form part of the top and bottom of the hood C. In the adjacent portions of the bottom of the hood and the bottom plates i' is formed an aperture J, which receives the neck 100

- and the adjacent portions of the chest and back of the speaker when the doors C^3 are closed, as shown in Figs. 5 and 7. This opening is made just large enough to closely fit 5 the chest and back of the person, so as to form as tight a closure as practicable.
- The doors of the hood may be provided with spring-hinges, as shown, which tend to keep them closed, and when such hinges are employed the doors are preferably provided with suitable catches for holding them open, if desired. The catches shown in the drawings consist of horizontally-swinging levers k , pivoted to the top of the doors near their hinges 10 and each provided at its front end with a hook or tooth k' , which interlocks with a vertical pin k^2 , projecting upwardly from the adjacent corner of the hood C , as shown in Figs. 1, 2, 15 3, and 6. The catch-levers k are yieldingly held in engagement with the pins k^2 by springs k^3 . Upon swinging the doors into the open position (shown in Fig. 2) the inclined faces of the catches k ride over the pins k^2 and automatically interlock therewith. The lugs k^4 , 20 25 which carry the pins k^2 , are arranged to serve as stops for limiting the opening movement of the doors. To release the doors, the hooked ends of the catches k are pulled outwardly to disengage them from the pins k^2 .
- As shown in the drawings, the upper rear portion of the hood is preferably curved downwardly and rearwardly and the rear portion of its bottom is curved to conform to the speaker's chest. 30
- The receiver B extends through one of the side walls of the hood C and is preferably made adjustable vertically, so that it can be raised or lowered to suit the speaker. For this purpose the receiver is mounted in a 35 vertical slide or carrier L , guided between the inner and outer walls of the adjacent side panel of the hood, as shown in Fig. 7. This slide is divided transversely into upper and lower sections, which are provided in their meeting edges with a circular opening m just large enough to receive the body of the receiver and with hooks and eyes m' or other suitable means for detachably connecting the sections together. The panel in which 40 45 the slide L is guided is provided with openings n of sufficient size to admit the large bell-shaped head of the receiver B . In order to place the receiver in the slide, the sections of the latter are disconnected and separated 50 sufficiently to allow the head of the receiver to pass between them, after which the sections are again brought together and recoupled. The slide is held in position by its frictional contact with its guides. 55
- As the receiver is supported by the hood C when my improved hood is used, it is necessary to normally hold the forked switch-lever B' in its depressed position by means independent of the receiver. I prefer to employ 60 for this purpose a cord o , attached to the switch-lever and provided at its lower end

with a tassel or other enlargement o' , which engages under a forked holder o^2 , secured to the battery-case P of the telephone or other support. 70

A person desiring to use a telephone equipped with my improved hood opens the doors C^3 , enters the hood, and allows the doors to close again under the action of their spring-hinges, the hood inclosing only the head and neck of the speaker. He then seizes the receiver and adjusts it to his ear, if necessary, releases the cord o from its holder o^2 to allow the switch-lever B' to ascend, and then calls the central office. As the hood is 80 closed on all sides and practically sound-proof, the speaker is not disturbed by noise outside of the hood and his conversation cannot be heard by others. 85

The hood being comparatively small occupies little space and can be used in locations where an ordinary telephone-cabinet would be impracticable, while its cost is much less than that of the ordinary cabinet. The hood can, moreover, be readily applied to ordinary 90 telephones without requiring any change in the construction or arrangement of the instruments, and if it should be desired to remove the hood at any time this can be quickly done by simply loosening the fastening-screws 95 of the attaching-hooks e and slipping the hood vertically off the face-plate a of the transmitter.

In the drawings the catches k are shown as applied to the top of the hood; but they could 100 obviously be otherwise arranged.

I claim as my invention—

1. A cabinet adapted to be applied to a telephone-transmitter, and consisting of a closed hood having a door for admitting the head of 105 the speaker, and provided in its bottom with a neck-aperture and in its rear wall with an opening arranged to register with the diaphragm of the transmitter, substantially as set forth. 110

2. A cabinet adapted to be applied to a telephone-transmitter and consisting of a closed hood provided at its front end with horizontally-swinging doors, in its rear wall with an 115 opening which registers with the transmitter-diaphragm, and in its bottom with a neck-aperture, substantially as set forth.

3. A cabinet adapted to be applied to a telephone-transmitter and consisting of a closed hood provided at its front end with horizontally-swinging doors, in its rear wall with an 120 opening which registers with a transmitter-diaphragm and in its bottom with a neck-aperture, springs arranged to close said doors, and catches for holding the doors open, substantially as set forth. 125

4. A hood or cabinet adapted to be applied to a telephone-transmitter and provided in its rear wall with an opening which registers with the transmitter-diaphragm, in its bottom 130 with a neck-aperture and at its front end with curved doors hinged to swing horizontally and

each provided at its upper and lower ends with horizontal, quadrantal plates which form part of the top and bottom of the hood, substantially as set forth.

5. The combination with a bracket having means for attaching it to a telephone-transmitter and provided on its front side with a vertical guide-bar, of a vertically-adjustable telephone-hood provided at its rear end with vertical ways which engage with said guide-bar, and having a neck-opening and a door for admitting the head of the speaker, substantially as set forth.

6. The combination with a bracket having means for attaching it to a telephone-transmitter, of a cabinet or hood engaging at its rear end with said bracket and capable of sliding vertically thereon, and having a neck-aperture and a door for admitting the head of the speaker, substantially as set forth.

7. The combination with a telephone-transmitter, of a vertically-adjustable hood guided at its rear end on the transmitter and provided with a neck-aperture and a door for admitting the speaker's head, and a counter-balance connected with the hood, substantially as set forth.

8. A closed telephone-hood having a door for admitting the speaker's head, a neck-opening arranged in the bottom of the hood, and a vertically-adjustable carrier for a telephone-

receiver guided on the side of the hood, substantially as set forth.

9. A closed telephone-hood having a door for admitting the speaker's head, a neck-opening arranged in the bottom of the hood, and a vertically-movable slide guided on the side of the hood and composed of sections provided in their meeting edges with an opening adapted to receive the body of a telephone-receiver, the hood being provided opposite the slide-opening with an aperture for admitting the enlarged head of the receiver, substantially as set forth.

10. A closed telephone-hood having a door for admitting the speaker's head, a neck-opening arranged in the bottom of the hood, a vertically-movable slide guided on the side of the hood and composed of sections provided in their meeting edges with an opening adapted to receive the body of a telephone-receiver, the hood being provided opposite the slide-opening with an aperture for admitting the enlarged head of the receiver, and means for separably connecting said slide-sections, substantially as set forth.

Witness my hand this 11th day of March, 1901.

EDWIN W. SMITH.
